UNITED STATES PATENT OFFICE.

FRANCIS DE SALES LUETTSCHWAGER, OF TUCSON, ARIZONA.

GARMENT-SUPPORT.

1,268,028.

Specification of Letters Patent. Patented May 28, 1918.

Application filed September 18, 1914. Serial No. 862,331.

To all whom it may concern:

Be it known that I, FRANCIS DE SALES LUETTSCHWAGER, a citizen of the United States of America, residing at Tucson, in the county of Pima and State of Arizona, have invented certain new and useful Improvements in Garment-Supports, of which the following is a specification.

This invention relates to garment supports and more particularly to that class of garment supports intended to be fastened to the waist band of trousers and engage the eyelet or button hole of suspenders.

The objects of the invention are:

15 To provide a support formed from one piece of metal wire;

To provide a support which may be easily attached to, or removed from the garment;

20 To provide a support which will be simple and cheap of manufacture, and easy and efficient in operation.

With these and such other objects in view as may hereinafter more fully appear, my invention consists in the novel arrangement 25 and construction of parts set forth in the following specification, more particularly pointed out in the claim, and which are shown in the accompanying drawings, wherein:—

30 Figure 1 is a front elevation of the device showing the same in place on a trousers band and engaging a suspender tab.

Fig. 2 is a front elevation of the device.

Fig. 3 is a top plan view.

35 Fig. 4 is a bottom plan view.

Referring to said drawings by numerals:—

The support is made of a single piece of

wire bent to provide a rectangular portion 1 having a shank 2 terminating in the outwardly disposed arms 3.

40 The outer ends of arms 3 are bent to provide the keepers 4, rear bars 5 of the pins, and the pins 6.

45 As will be readily understood, the pins 6 are inserted into the material of the trousers and the points thereof snapped into the keepers 4. The rectangular portion 1 is then inserted through the button hole of the suspenders so that the shank 2 is engaged, as shown most clearly in Fig. 1.

Having described my invention, what I claim as new and desire to secure by Letters Patent, is—

55 A garment support formed of a single piece of wire bent to form a depending shank, a cross bar at the lower end of the shank, oppositely disposed, laterally extending portions at the upper end of the shank, a downwardly bent portion at the outer end 60 of each laterally extending portion extending substantially parallel to the shank, a keeper formed on each downwardly bent portion, and the end of each downwardly bent portion bent to form a pin the end of 65 which is adapted to be engaged by the keeper.

In testimony whereof I hereunto affix my signature in presence of two witnesses.

REV. FRANCIS DE SALES LUETTSCHWAGER.

Witnesses:

T. M. SMITH,
H. S. SHANER.
